UNITED STATES PATENT OFFICE.

FREDERIC E. WORDEN, OF HUDSON, MICHIGAN, ASSIGNOR TO HAZEN MANUFACTURING COMPANY, OF HUDSON, MICHIGAN, A CORPORATION OF MICHIGAN.

WATER-CHANGE VALVE.

1,305,583.

Specification of Letters Patent.

Patented June 3, 1919.

Application filed March 8, 1918. Serial No. 221,146.

To all whom it may concern:

Be it known that I, FREDERIC E. WORDEN, a citizen of the United States, residing at Hudson, county of Lenawee, State of Michigan, have invented a certain new and useful Improvement in Water-Change Valves, and declare the following to be a full, clear, and exact description of the same, such as will enable others skilled in the art to which it 10 pertains to make and use the same, reference being had to the accompanying drawings, which form a part of this specification.

This invention relates to water change valves for well pumps and the like, and has 15 for its object an improved construction and arrangement of parts. The distribution valve and its packing nut may be located in the pump system at a point below frost level and yet may be easily removed for repair 20 without requiring the disconnection of one or both of the distributing pipe connections of the valve shell.

In the drawings:

Figure 1 is an elevational view of a pump 25 and its connected distributing pipes, showing the position of the distributing valve casing relatively to the other parts.

Fig. 2 is a partly sectional view of the 30 various chambers of the valve shell and of the connections to the various pipes, the valve being in position to direct the flow of water into the upper or spout pipe.

Fig. 3 is a view similar to Fig. 2, showing 35 the valve in a different seating position, so as to direct the flow into the underground ditch or watering trough pipe.

Fig. 4 is a sectional plan view taken along the line $\alpha-\alpha$ of Fig. 2.

A indicates a well pump, whose supply 40 branch B extends down into a well or other source of supply, the piston C being adapted to reciprocate up and down in the usual way as the handle D is actuated. The upper end of the pipe B is connected with the 45 chamber F of the casing E, and in the side wall of the chamber F is located a passage G leading to the chamber H, which in turn is connected by a passage J with a valve chamber K, one end of which opens into the 50 upper end of the ditch or watering trough pipe L, and in the other end of which is located a passage P which leads into the pocket or chamber Q, with which the lower end of the spout pipe R is connected. The 55 opening to the ditch pipe L is protected by a

coupling M having a valve seat N, against which the valve O seats when it is desired to direct the flow of water into the spout pipe R. Axially in line with this seat N is the removable valve shell S, against whose end 60 T the valve O seats when it is desired to direct the flow of water into the ditch or watering trough pipe L. The screw threaded lower end U of this valve shell engages a complementarily threaded portion of the inner surface of the chamber K, while the upper portion, which engages outside of the casing E, is threaded to receive a removable packing nut V, through which the stem W of the valve O passes, its upper end reaching 65 above the ground to a convenient position for manipulation, adjacent the pump handle. An aperture X in the side of the shell S affords communication between the chamber K and the pocket Q, leading to the spout 70 pipe R.

From the foregoing it will be evident that by raising or lowering of the stem W the valve T is caused to seat against one or the other of the seats N and T, thereby directing 75 the flow of water into the spout pipe R or ditch pipe L as desired. At the same time the entire valve shell S, and the valve O with its stem W can be easily removed from the chamber K by unscrewing, without 80 in any way disturbing any of the other connections leading to or from any part of the casing E. At the same time, the packing nut V, constituting as it does a portion of the removable valve shell S is not required 85 to be above the ground surface and therefore exposed to freezing, but is located in 90 the ground below the frost line.

For the holding of the stem W in raised position, I have shown its upper end screw 95 threaded as at Y for engagement through a complementarily threaded bracket or projection Z on the frame of the pump. It is obvious, however, that other equivalent constructions for effecting this purpose could be 100 employed, without departing in any way from the spirit of my invention.

What I claim is:

In a valve, in combination with an outer shell having a plurality of serially connected 105 apertured chambers, a supply pipe connected with one of the end chambers, discharge pipes connected with each of two others of said chambers, an axially disposed valve seat in one of said chambers, a shell mem- 110

ber removably located partly within and partly outside of that chamber wherein said valve seat is located, its inner end forming an oppositely disposed companion valve seat, a piston member disposed between said valve seats in position to seat against either and to thereby shut off the flow to one or the other of the discharge pipe apertures, an actuating stem for said piston member extending through said removable shell mem-

ber, and a packing nut through which said stem extends to an outside point, located on the outer end of the valve shell.

In testimony whereof, I sign this specification in the presence of two witnesses.

FREDERIC E. WORDEN.

Witnesses:

P. J. DILLON,
W. R. THOMPSON.
